US0D1096853S

(12) **United States Design Patent** (10) **Patent No.:** **US D1,096,853 S**
(45) **Date of Patent:** **** Oct. 7, 2025**

(54) **FLUID PUMP**

(71) Applicant: **Wagner Spray Tech Corporation**,
Plymouth, MN (US)

(72) Inventor: **Douglas P. Pozanc**, Winona, MN (US)

(73) Assignee: **WAGNER SPRAY TECH
CORPORATION**, Plymouth, MN (US)

(**) Term: **15 Years**

(21) Appl. No.: **29/915,903**

(22) Filed: **Nov. 6, 2023**

(51) LOC (15) Cl. **15-02**

(52) U.S. Cl.

USPC **D15/7; D23/225**

(58) **Field of Classification Search**

USPC D15/7-9; D23/225, 231, 232; D13/107;
D10/86

CPC F04B 1/005; F04B 33/00; F04B 33/005;
F04B 15/00; F04B 15/02; F04D 13/06;
F04D 25/0673; F04D 25/08

(57) **CLAIM**

The ornamental design for the fluid pump as shown and described.

DESCRIPTION

FIG. 1 is a perspective view of the fluid pump.

FIG. 2 is a front view of the fluid pump.

FIG. 3 is a rear view of the fluid pump.

FIG. 4 is a left side view of the fluid pump.

FIG. 5 is a right side view of the fluid pump.

FIG. 6 is a top view of the fluid pump; and,

FIG. 7 is a bottom view of the fluid pump.

The details shown in broken lines form no part of the claimed design.

1 Claim, 7 Drawing Sheets
